UNITED STATES PATENT OFFICE.

ELIJAH MISENER MIERS, OF WIARTON, ONTARIO, CANADA.

ICE-SKATE.

1,263,092.

Specification of Letters Patent. Patented Apr. 16, 1918.

Application filed July 26, 1917. Serial No. 182,956.

To all whom it may concern:

Be it known that I, ELIJAH MISENER MIERS, of the town of Wiarton, in the county of Bruce and Province of Ontario, Dominion of Canada, have invented certain new and useful Improvements in Ice-Skates; and I hereby declare that the following is a full, clear, and exact description of the same.

My invention relates to improvements in ice-skates, its main object being to embody in the structure of the skate, a resilient function, whereby the jarring effect of the impact of the skate with the unyielding ice surface is practically nullified.

Such improved construction has the beneficial effect of a shock absorber, which results in a marked conservation of the strength of the skater, and is, therefore, productive of higher individual energy in maintaining speed and endurance, as the cushioning of the jarring impact largely tends to eliminate fatigue.

This beneficial effect is particularly advantageous in racing contests, where long or even short distances are to be covered, and the necessity of maintaining high speed is absolutely essential.

To these ends, my invention consists of certain details of construction, all of which will be hereinafter described and pointed out in the claim.

In the drawings:

Figure 1, is a side elevation of my improved skate;

Fig. 2, is a central vertical section of one of the sockets with the spring-pressed plunger in engagement therewith;

Fig. 3, is a bottom plan view of one of the plungers; and,

Fig. 4, is a similar view of one of the sockets.

Referring to the drawings, 1 is the runner-blade having its ends 2, 2, inclined upwardly and inwardly. 3 and 4 are cylindrical sockets extending vertically from the runner-blade and being rigidly connected thereto, and located on the forward or sole

portion of the skate. The front socket 3 is also rigidly connected to the end 2 of the runner-blade. 5 is another cylindrical 50 socket at the rear or heel portion of the skate, and being rigidly connected to the runner-blade 1 and its end 2.

A cylindrical plunger 8 is provided for each vertical socket 3, and has at its upper 55 end, the lugs or wings 9, 9, for attachment to the sole and heel plates.

12 is the sole plate rigidly secured to the lugs or wings 9, 9 of the two forward plungers, and 13 is the heel plate similarly secured to the rear plunger.

14 is a coiled spring having vertical play within each plunger and its socket, its upper end being rigidly secured to the sole or heel plate and its lower end rigidly secured 65 to the socket floor.

In action, the weight of the skater and the force of impact sends the plungers down in their sockets, against the action of the interposed springs, which, with the recoil of 70 the springs, imparts a resiliency to the plungers, thereby producing the desired effect.

Having thus fully described the nature of my invention, what I claim as new and desire to secure by Letters Patent, is:—

A spring skate comprising a runner-blade, twin vertical sockets rigidly connected to the front portion of the runner-blade, a vertical socket rigidly connected to the rear portion of the runner-blade, hollow plungers 80 having vertical play within the front and rear sockets, a sole plate rigidly connected to the front twin vertical sockets, a heel plate rigidly connected to the rear vertical socket, and springs secured at their upper 85 ends to the sole and heel plates, and at their lower ends to the socket floors, and having vertical play within the plungers and sockets.

Wiarton, July 16th, 1917.

ELIJAH MISENER MIERS.

Signed in the presence of—

S. B. CAMERON,

T. E. AUBER.
